WELL SWAB

George A. Rayner, Smithville, Tex.

Application May 19, 1941, Serial No. 394,193

1 Claim. (Cl. 103—225)

This invention relates to a well swab especially adapted for removing foreign matter from the walls of a well or the casement thereof, and has for the primary object the provision of a device of this character which may be successfully employed on a line for raising and lowering thereof in the well and which will be self-releasing if stuck in the well from any cause by simply placing slack in the line.

Another object of this invention is the provision of a device of the above stated character which will be durable and inexpensive to manufacture and will be free of the disadvantages of the conventional type of well swab which when hung in a well sometimes destroys the well for further use or requires a large expenditure of time and labor in the removal thereof from the well, necessitating the pulling of the well casement in order that the swab be dislodged and removed.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which

Figure 1 is a side elevation partly in section illustrating a well swab constructed in accordance with my invention and showing the same being lowered in a casement of a well.

Figure 2 is a view similar to Figure 1 showing the swab in an operative position or on its upward movement in the well casement and in the act of removing foreign matter from the walls of the casement.

Figure 3 is a side elevation, partly in section, illustrating the swab in a self-releasing position.

Figure 4 is a sectional view taken on the line 4—4 of Figure 2.

Figure 5 is a sectional view taken on the line 5—5 of Figure 2.

Referring in detail to the drawings, the numeral 5 indicates a cylinder type body of the swab, the latter being designated generally by the character 6. The opposite ends of the body 5 are externally screw threaded to receive caps 7 of the spidered type. The caps slidably support a rod 8 which extends entirely through the body 5 and has each end screw threaded. One end of the rod is detachably connected to a cable or line attaching rod 9 by a coupling 10 which has threaded connection with the rods 8 and 9. The

other end of the rod 8 has mounted thereon a disc type valve element 11 removably held on said rod by a nut 12 threaded on the latter-named end of the rod 8. The valve element is coactive with one of the caps 7 in closing the lower end of the body 5 when the swab 6 is suspended by a cable or line 13 for operation in a well or the casement thereof, indicated by the character 14.

The caps 7 slidably retain the rod 8 centered 10 within the body 5 and said rod within the body 5 and spaced a limited distance from the uppermost cap 7 is equipped with a spring seat 15. One end of an expansion spring 16 engages the seat 15 while the other end engages the uppermost cap. 15 The action of the spring normally is to move the valve element 11 away from the lower cap 7. However, when the device is suspended on the cable 13 and due to its weight compresses the spring 16 bringing the valve element 11 into 20 seated engagement with the lowermost cap 7 for closing the body 5.

Spaced cupped seats 17 are formed on the exterior of the body 5 for supporting thereon cup-shaped swab elements 18, preferably constructed 25 of yieldable reinforced material, such as rubber or the like. The swab elements fit within the cupped seats 17 and flare outwardly so as to contact the walls of the casement when the swab is located therein.

The body 5 is provided with ports 19 placing 30 the interior of the swab elements in communication with the interior of the body 5 so that fluid within the body 5 may enter the swab elements and flex the latter outwardly to snugly fit the walls of the casement.

In operation, the swab 6 is lowered into the well with the swab elements contacting the walls of the casement and when the swab reaches the fluid of the well, slack is allowed to occur in the line 13 permitting the spring to unseat the valve element 11 whence the fluid of the well may enter the body 5 and pass into the swab elements. The weight of the fluid within the swab elements tends to urge the latter into tight contact with 40 the walls of the casement and by drawing upwardly on the swab by the line 13, the swab elements frictionally rubbing against the walls of a casement remove foreign matter therefrom.

During the upward movement of the swab, the 45 weight thereof and the weight of the fluid on the swab elements being on the line overcomes the action of the spring and the valve element is seated to prevent the escape of fluid from the device.

Should the swab, during its upward movement

in the casement of the well become stuck or hung, slack is permitted to occur in the line 13 and the spring acts to unseat the valve element 11 and allow the fluid to flow from the body 5 and consequently from the swab elements, relieving the latter of the weight of the fluid thereon so that on another upward pull on the line the swab will become released from its stuck position.

While I have shown and described the preferred embodiment of my invention, it will be understood that minor changes in construction, combination and arrangement of parts may be made without departing from the spirit and scope of the invention as claimed.

Having thus described the invention, what is claimed as new is:

In a well swab, an elongated hollow body, spider type caps applied to the ends of said body and one of said caps providing a valve seat, a rod 15
slidable through the caps and body and supported axially of the latter by the caps and adapted to

have one end thereof connected to an operating line for vertical movement in a well, a valve element secured to the other end of the rod to co-operate with the seat of one of the caps in opening and closing the lower end of the body, a spring acting on the rod within the body and bearing against one of the caps to unseat the valve element and the latter being seated by the load of the body on the operating line, said body 20
having groups of openings arranged annularly thereof, cup-shaped seats mounted on the body below said openings, and flexible inverted substantially conical shaped cups mounted in the seats with the major portions thereof unattached and overlying the openings to receive fluid from the body to force said unattached portions of the cups against walls of the well for removing foreign matter therefrom during reciprocation of the body by the line.

GEORGE A. RAYNER.
